UNITED STATES PATENT OFFICE.

THOMAS FRANCUS BUCKLEY, OF LOCK HAVEN, PENNSYLVANIA.

WOOD-BUNDLING MACHINE.

SPECIFICATION forming part of Letters Patent No. 425,064, dated April 8, 1890.

Application filed January 4, 1890. Serial No. 335,842. (No model.)

To all whom it may concern:

Be it known that I, THOMAS FRANCUS BUCKLEY, of the city of Lock Haven, county of Clinton, and State of Pennsylvania, have invented certain new and useful Improvements in Wood-Bundling Machines, of which the following is a specification, reference being had to the accompanying drawings.

The object of my invention is to provide a simple, inexpensive, and economical machine for pressing small pieces of wood into bundles, which is a merchantable shape for kindling-wood.

The structure of my machine makes it of small first cost. A number of machines may also be arranged along a single shaft without a multiplicity of gearing, so as to make it exceedingly economical in use.

My invention consists in the construction and arrangement of parts, which I shall hereinafter set forth in detail, and succinctly describe in my claims.

In the accompanying drawings, Figure 1 is a front elevation of my machine; Fig. 2, a side elevation of the running-gear of same detached; Fig. 3, an oblique elevation of the bundling mechanism; Fig. 4, a cross-section of the main gear-wheel; Fig. 5, a perspective of the clutch-hub and section of main shaft, and Fig. 6 a front elevation of a modified form of gearing for operating my machine.

Referring to the letters upon the drawings, A represents a revolving shaft provided with ordinary journals. (Not shown in the drawings.)

B is another shaft.

C indicates a cog-wheel secured to the shaft A and meshing with another gear D, turning loosely upon the shaft B, upon one side of which is secured the collar E, and upon the other side of which is secured the clutch-hub F and the knockers G, having inclined sides H.

I is a clutch of any ordinary construction to fit the clutch-hub F, and is keyed to the shaft B, so as to allow it to move freely longitudinally, but not to revolve.

J indicates a hand-lever pivoted to a support—as, for instance, the support K—upon the upright L.

M is a projection upon the lower end of the lever J at the same distance from the shaft as the knockers G.

N indicates an annular groove in the clutch to receive the bifurcated end O of the hand-lever, so as to allow the clutch to be freely operated by the movement of the latter.

P P indicate crank-bearings on the shaft B, and Q a crank-bearing on the same shaft, extending in an opposite direction. To the bearings P P are secured the vertical pitmen R 60 R, and to the bearing Q another vertical pitman S.

T is a band connected at each end to the pitmen P P.

U is a saucer secured to the pitman S. 65

V is an operating-table provided with apertures to receive the pitmen and the hand-lever.

W is a slot in the band T to receive a binding twine or rope. 70

X X indicate guides upon the band T for the saucer U.

Y indicates a cast-iron back bolted to the table V, and may be adjustable, so as to gage the length of wood to be bound and keep the 75 ends even.

The operation of the machine is as follows: The shaft A and the cog-gears are at all times, when in use, revolving, the gear D turning loosely upon the shaft B. If, now, the saucer 80 U is filled with wood ready to be packed, upon clutching the gear D to the shaft B by means of the hand-lever the shaft B is caused to revolve and a double reciprocating movement is imparted to the saucer U and the band 85 T, so as to press the wood tightly together.

As soon as the gear D has made a half-revolution one of the knockers G comes in contact with the projection M upon the hand-lever and releases the clutch action between the 90 shaft B and the gear. The saucer and the band continue to bear the same relative position, so that the bundle may be tied and removed and the operation repeated as before.

It is obvious that a number of my machines 95 may be operated by the same crank-shaft B, so that one long table may be occupied by a number of machines.

What I claim, and desire to secure by Letters Patent of the United States, is—

1. In a wood-bundling machine, the combination of two crank-bearings and a band with 5 an opposite crank-bearing and a saucer, whereby a reciprocating action is imparted to each, substantially as set forth.

2. The combination of a band T, the saucer U, the crank-shaft B, provided with the bearings P and Q, the gear D, turning loosely upon the crank-shaft and provided with the clutch- 10

hub F, the clutch I, the hand-lever to operate the same, the knockers G upon the gear, and the projection M upon the lever, substantially as set forth. 15

In testimony of all which I have hereunto subscribed my name.

THOMAS FRANCUS BUCKLEY.
